FRANCIS W. COOPER AND HENRY STEADWORTHY, OF MONTREAL, QUEBEC, CANADA.

ANCHOR AND CLIP FOR RAILS AND THE LIKE.

Application filed August 11, 1922. Serial No. 581,153.

To all whom it may concern:

Be it known that we, FRANCIS W. COOPER and HENRY STEADWORTHY, both subjects of the King of Great Britain, and both residents of the city of Montreal, in the Province of Quebec and Dominion of Canada, have invented certain new and useful Improvements in Anchors and Clips for Rails and the like, of which the following is a full, clear, and exact description.

This invention relates to improvements in anchors or clips to hold a rail, frog or the like to a base plate, rail plate or other structure.

15 The primary object is to provide an anchor or clip applicable to a standard tie plate or the like to connect a rail thereto and to hold the rail under ordinary conditions against longitudinal movement in either direction relatively to the plate.

20 A further object is to provide a device which will not become loosened by vibration nor by wave movement of the rail due to a train moving thereover.

25 A still further object is to provide a device of simple form, small size and light weight which may be easily and cheaply manufactured and sold at low cost.

30 Another object is to provide a device which may be easily assembled on or removed from a rail, but which will be substantially proof against malicious removal or removal by an accidental blow.

35 Still another object is to provide a device of this character consisting of only two parts, so formed and constructed that they cannot be assembled otherwise than in the proper manner.

40 An additional object is to provide a device which may be attached without the use of special tools other than those ordinarily used in track laying.

45 A further additional object is to provide a device which is applicable without adjustment to practically all sizes of rails or at least to a very wide range of sizes.

50 A still further additional object is to provide a rail clip or anchor which will hold a rail against over-turning, even if a part of the anchor is broken or removed.

55 Another additional object is to provide a rail clip or anchor particularly adapted for use with shouldered tie plates and so constructed as to bind a rail down on the tie plate and at the same time clamp the rail against the tie plate shoulder, whereby the

rail is doubly held and is prevented from riding up on the tie plate shoulder.

Various other objects and advantages of the invention will be readily ascertained 60 from the following description.

The invention comprises a substantially rigid double-hooked clip member adapted to hook under a tie plate or other device and over a rail base and to be secured in position primarily by means of a flexible key driven between the clip and rail base, the said clip having a portion to hold the same against tilting away from the rail in a manner which would impair or destroy the grip of the device. The clip is adapted to hook under a tie plate preferably by means of members projecting through spike or other holes in the tie plate, the said members being of such size and form that special manipulation of the clip is necessary to enable its attachment to or detachment from a plate and rail, whereby the possibility of accidental or malicious removal is greatly minimized. Furthermore, the device is so constructed that when suitable tie plates are used the usual number of ordinary track spikes may still be used, the capabilities of the clip being such that these spikes when properly driven are, in a measure, anchored 70 to the tie plate and thus guarded against partial withdrawal by rail undulation.

In the drawings which illustrate one principal embodiment of the invention, with certain minor modifications:—

Fig. 1 is an end elevation of the device in operative position.

Fig. 2 is an outer side elevation of the device in operative position.

Fig. 3 is a plan view.

Fig. 4 is an inner side elevation, the rail and tie plate being removed.

Fig. 5 is a side elevation of a key before insertion.

Fig. 6 is an end elevation of one form of 100 key.

Fig. 7 is a fragmentary end elevation showing another embodiment of the invention.

Referring more particularly to the drawings, 11 designates a tie plate of any suitable pattern, preferably having a shoulder 12, against which one edge of a rail base may bear, and provided with holes 13 and 14 for the passage of spikes 15 and 16 to secure 110 the rail 17 and tie plate to a tie. At the shouldered end of the plate the spike holes

13 are of the ordinary rectangular form and the holes 14 at the opposite edge of the tie plate are preferably of the familiar form shown in Figure 3, permitting the insertion of a spike in either of two positions according to the size of a rail.

According to the present invention, the anchor or clip comprises a body member, designated as a whole by the numeral 18, and 10 a key, designated as a whole by the numeral 19. The body of the clip is split at its lower edge into three tongues, the two outer-most of which, designated 20, are comparatively narrow and of a size to pass snugly through 15 the inner part of the spike holes 14, as clearly shown. While the existing spike holes are convenient for the purpose, the invention is obviously not limited to their use. The central tongue, designated 21, occupies 20 the space between the spike holes and is bent substantially at a right angle, or a little less, to the body of the clip and is designed to lie on the upper surface of the tie plate, as clearly shown in Figure 1. The extremities 25 of the fingers 20 are bent sharply at substantially right angles to the body of the clip and in the opposite direction to the finger 21 to form hooks 22 which will just pass through the spike holes 14 and which will engage under that portion of the tie plate immediately beneath one edge of the rail base. The bending or forming is done in such a way that there is substantially no curvature into the outer surface of the clip but the outer surface is carried straight down to the bottom of the hook, so as to form a substantially sharp edge, designated 23. The upper end of the clip is bent to semi-circular form and to the same side as 30 the hooks 22, so as to form a hook 24 which will over-hang the edge of a rail base. The clips are preferably made of flat steel bars of suitable width and thickness, the width of the bar being the width of the clip between 35 its vertical edges. The bar is cut to suitable lengths forming rectangular blanks which are then split from one end to form the three tongues above mentioned and bent over at the opposite cut edge to form the upper hook. It will thus be seen that all 40 bending of the blank is done across the fibre or grain of the material, so that there is little possibility of the hooks breaking, either in formation or in use, as might readily occur if the bending was done with the grain. While this is the preferred method of construction, it must not be assumed that the invention is in any way limited thereto. It 45 will also be seen that there is absolutely no waste in the formation of the clip. In bending the material to form the upper hook 24 the bend is formed slightly lower down in the centre of the material than at the vertical edges, as clearly shown in Figure 2, so 50 that the under surface or throat of the hook 55

curves downwardly from its ends to its centre. At the centre a recess 25 is provided in the throat of the hook. Preferably this recess is curved as shown in Figure 2 but may be a square shouldered recess as shown at 25^a Figure 4, or even an aperture 25^b as shown in Figure 5. As will be clearly seen the throat of the hook slopes downwardly from both ends to the centre in order that a key driven between the rail and hook 24 will be gradually compressed between the rail and the sloping portions 26 of the hook throat and will, when fully driven, spring into the centrally disposed recess which will hold it against movement. The form of recess depends upon the relative hardness of the material in the members and also to a certain extent upon the shape of a key to be used with the clip. In its holding effect the aperture 25^b does not differ from the square shouldered recess 25^a, but from a manufacturing standpoint the aperture may be more easily provided than a recess as it may be punched out prior to the forming of the clip, while the recess must be formed simultaneously with or after formation of the hook 24. The form of recess shown in Figure 2 is perhaps preferable to the other forms, as it will present a much greater surface for frictional engagement with a key, 95 but under certain circumstances the shouldered type of recess may be preferred.

The key 19 which operates to hold the clip in position is preferably formed of a round bar of a size sufficient to fit snugly in the curved throat of the hook 24, as clearly shown in Figure 1. The key is of springy or resilient material and is bent so as to provide a hump 27 intermediate its ends which will bear in the hook 24 while the ends 100 are designed to bear on the upper surface of the rail base. The length of the key is only slightly greater than the width of the clip, as clearly shown in Figures 2 and 4. Preferably the ends of the key are flattened on 105 the opposite side from the hump as at 28, to provide bearing surfaces of suitable size for engagement with the rail. These surfaces may be plain or may be corrugated or otherwise roughened, as indicated at 29, Figure 110 4. These surfaces are preferably produced by flattening the ends of the key in such a manner as to position the bearing surfaces 115 slightly out of parallel with the normal axis of the key. In other words, the flattening produces a slight tapering at the ends of the key, which has the effect of distributing flexion stresses throughout the length of the key in the well known manner and thus relieving the central part of the key of a portion of the stresses due to flexion in driving. The flattening operation is preferably performed in such a manner as to produce bearing surfaces 28 which are slightly wider 120 than the diameter of the key proper, so that 125 130

the ends of the key are of such size that they cannot be inserted in the hook of the clip. This feature of construction makes it impossible for the key to be inserted upside-down. This widening of the ends of the key is shown in a possibly somewhat exaggerated form in Figure 1. A flattening operation of this character may be open to the objection that it produces a very shallow surface for driving the key into position. This objection may be overcome by flattening only one side of the key, as shown in Figure 6, the metal to form a wider base being obtained by punching or flattening the sides of the key above the base so as to produce possibly a parabolic end profile, as shown, without any reduction in the vertical dimension of the end. This method of forming the flattened end will not produce the taper towards the ends of the key, which has been already described and therefore in order to obtain both the tapering and the shape of end suitable for driving, the ends of the key may be slightly headed as illustrated at 30, Figure 5. It will be understood that the various methods of forming the key end are suggestive and not in any way limitative. The formation of the key is preferably such that in its initial form it rests only at its extreme ends on a flat surface, such as a rail base, and the top of the central hump projects considerably above the central part of the hook throat, as shown in Figure 5, so that when the key is driven between the rail base and hook 24 it is subjected to considerable friction and flattening which results in bringing the bearing surfaces 28 firmly down onto the rail.

The method of applying the device is as follows:—The hooks 22 of the clip body are passed down through the holes 14 of a tie plate or the like, the clip being preferably canted slightly toward the rail to assist in the operation. When the hooks 22 are through the plate the whole clip is moved toward the rail so as to engage the hooks under the tie plate and bring the body of the clip against the edge of the rail. This movement of the clip toward the rail is preferably accomplished by driving standard track spikes down through the outer portions of the holes 14, owing to the fact that the clip grips the tie plate rather snugly between its hooks 22 and central finger 21, there being preferably a slight flexion of the finger 21 in the final positioning. The spikes are driven at a slight inclination as shown in Figure 1, so that they bear against the back corner 23 of the hooks 22 and support these hooks against flexion and backing away from the rail when under load. When the spike is driven home the over-hanging back portion of the head engages the outer surfaces of the clip and presses the same very tightly against the rail, at the same time driving

the rail against the plate shoulder 12. The throat of the spike also engages the upper outer edge of the hole 14 and it is owing to this bearing point that the thrust toward the rail is obtained. It will be noted that 70 the spike, therefore, supports the clip at points above and below the plate and also that the plate supports the head of the spike so that it cannot tip back in the well known manner. The spike is very tightly wedged 75 in place and is thus held against drawing due to rail undulation. The central tongue 21 of the clip holds the same against tipping away from the rail and the engagement of the spike with the lower corner 23 holds it 80 against tipping towards the rail. One end of the key 19 is now inserted under hook 24 as shown in Figure 5, and the key driven in by means of a hammer until its central hump 27 enters the recess of the hook. In 85 this driving the key is flexed and serves to bind the rail very tightly down on the tie plate. The key being formed of round bar and the hook throat being formed accordingly it is obvious that the key will easily 90 rock in the hook to assume a position perpendicular to the inclined upper surface of the rail base and obtain a secure bearing on its flat end surfaces 28. This inclination of the key from the vertical causes a lateral 95 thrust and tends to urge the rail against the plate shoulder 12. The position of the key also tends to cant the clip away from the rail but in such movement is restricted by the central tongue bearing on the plate and also by the spike. It will be understood that the invention is not in any way limited to 100 the above described manner of applying the device, so that the order of inserting the spikes and key may be reversed if desired. 105

The device is almost entirely proof against accident or mis-use. The formation of the key makes it impossible to insert the same upside-down. If a key should break there will be a very considerable grip on the rail 110 still exerted by reason of the spike jamming the clip against the rail. A broken key does not release the rail for the reason that the over-hanging hook 24 will hold the rail against over-turning, even if the parts of the broken key should be removed. If the parts remain in place the rail cannot be tipped enough to bring its base into engagement with the tip of the hook 24 as the key 115 constitutes a filler permitting but very little movement. The breakage of a key does not in any way release the clip from the plate for the reason that the spike holds the clip against backing away from the rail and the spike and finger 21 hold it against tipping away from the rail. If the spike head should tear off the anchorage is little 120 if any affected as the shank of the spike remaining in the aperture 14 will hold the clip against backing away from the rail and 125

loosing its grip. Even if the spike is withdrawn the clip cannot back away from the rail to any appreciable extent by reason of the friction between the clip hooks 22 and the upwardly flexed finger 21 and the rail plate. Also, the key holds the clip against tipping toward the rail in a manner necessary to enable its hooks 22 to be drawn through the spike holes 14 even if the clip backed away to the full extent permitted by the holes 14, the spring of the key is sufficient to take up any such movement, and the key will therefore be so tight even after such movement that it must be driven out with a hammer and follower. In the application of the device it is impossible to over-drive the key and thus strain any part of the device, since the proper driving of the key is the maximum possible amount and further driving requires a follower and serves only to release the key. When properly driven the ends of the key are substantially flush with the ends of the clip and therefore the question of whether the key has been sufficiently driven can never arise as a glance will show if a key has been driven. The key being entirely enclosed by the hook of the clip it is effectually guarded against loosening by accidental or malicious blows. The whole device is small, compact and inexpensive and lies so low and close against the rail base that it does not form any appreciable obstruction along the track, nor is it liable to be struck and damaged by any passing object. The central finger 21 constitutes a filler between the spike heads which, to a certain extent, protects and supports the spike heads and is in turn protected by them. When using properly apertured tie plates as shown, the use of this finger does not in any way decrease the normal spiking down capacity and, in fact, increases the efficiency by practically locking the spikes and plate together, so that after any upward movement which might slightly draw a spike the same is driven back upon the subsidence of the plate. The projection of the device below the plate is so little that it does not in any way interfere with proper seating of the plate on a tie. In addition to the feature of guarding the rails against longitudinal movement it serves also in its application to square up the tie plates with the rails and to hold the plates in proper relation to the rails, so that it is impossible for the rail to ride on the shoulder rib 12 of the plate as some times occurs when plates have been carelessly placed or have become loosened. Moreover, the finger 21 will tend to hold a rail against tipping sufficiently for its outer edge to rise above the plate rib. It will be noted that a key is subjected in driving to flexion greater than normally obtains when the key is properly seated and in this

way each key is tested in driving. If a key does not spring sharply into the recess 25 it will be at once observed and will indicate that the key is either cracked or soft. While, for convenience of illustration, only one spike has been shown in position in Figures 2 and 3, it will be understood that in practice spikes may be and are preferably driven through both apertures 14.

Various minor modifications may be made, such as corrugating the hump of the key similarly to its ends and forming the key seat 25 with corresponding corrugations adapted to interdigitate with the key corrugations to hold the same more firmly.

In Figure 7 there is illustrated another modification in which an equivalent of the hooked clip member, designated 18^a, is fixed to the plate 11^a, either integrally by rolling, forging or casting, or by welding, riveting or bolting.

Heretofore reference has been made to spring keys only but it will be understood that the invention contemplates also the use of non-resilient keys, the desired resiliency being obtained in the clip member.

While no device will hold the rails absolutely against longitudinal movement if sufficient force is applied, it is believed from the result of experiments, that the device herein described will hold the rails so tightly to the tie plate that any movement of the rails will be accompanied by corresponding movement of the tie plates and ties themselves and therefore it is deemed proper to state that this device will positively hold the rails against longitudinal movement in either direction on the ties, not only when first applied but also after long periods of use, owing to the continuous and automatic spring action of the resilient member which keeps the device always tight on the rail and plate. Consequently, when used on all ties, this device would hold them in constant position with respect to a rail and would resist bunching of ties under derailed wheels.

It will be understood that the invention resides in the clip member and key and in the combination of these with existing external elements which are not in any way limited to the form of plate and spike illustrated but may, within the scope of the invention, be devices of other forms and for other purposes.

Having thus described our invention, what we claim is:—

1. A device of the class described, comprising a member hooked at its upper and lower ends to engage under a tie plate and to overlie a rail base, and a resilient key adapted to be driven between the upper hooked end of the member and the rail base to yieldingly connect the plate and rail.

2. A device of the class described, comprising a member hooked at its upper and

lower ends to engage under a tie plate and to overlie a rail base, said member being formed for engagement at points above and below the plate with a track spike driven through the plate to be held by such engagement against tipping and disengagement from the plate.

3. A device of the class described, comprising a member hooked at its upper and lower ends to overlie a rail base and underlie a tie plate, a projection from said member adapted to engage a tie plate and hold the member against tipping away from a rail, and a resilient key insertable between the upper hooked end of the member and the rail base to hold the member against tipping toward a rail.

4. A device of the class described, comprising a clip member hooked at upper and lower ends and adapted to overlie a rail base and underlie a shoulder tie plate, and a resilient key insertable between the upper hooked end of said member and a rail base in position to hold a rail down on a tie plate 25 and to urge a rail laterally against a shoulder on the tie plate.

5. A device of the class described, comprising a clip member hooked at upper and lower ends and adapted to overlie a rail base and underlie a tie shoulder plate, and a resilient key insertable between the upper hooked end of said member and a rail base in position to hold a rail down on a tie plate and to urge a rail laterally against a shoulder 35 on the tie plate, and means to hold the clip against tipping away from a rail under the lateral thrust.

6. A device of the class described, comprising a clip member hooked at its upper and lower ends to overlie a rail base and underlie a tie plate, a resilient key adapted to be driven between the upper hooked end of the clip and the upper surface of a rail base, and a projection from said clip member on 40 the opposite side thereof from the key engageable with a tie plate to hold the clip against movement away from a rail.

7. A device of the class described, comprising a clip member having at its upper end a hook adapted to overlie a rail base and at its lower end a pair of spaced hooks adapted to underlie a tie plate, and a key insertable between the upper hooked end of the clip and a rail base, said clip and key being formed for engagement at a point between vertical planes containing the lower hooks.

8. A device of the class described, comprising a clip member hooked at its upper and lower ends to overlie a rail base and underlie a tie plate, the hook of the upper end extending from side to side of the clip and sloping downwardly from the sides toward the centre, whereby on the driving of

a key between said upper hook end and the 65 rail base a wedging action will result.

9. A device of the class described, comprising a clip member hooked at its upper and lower ends to overlie a rail base and underlie a tie plate, the upper hook of said 70 member sloping downwardly from the sides toward the centre to provide a centrally disposed key seat, the member being recessed in the said seat portion to releasably hold a key.

10. A device of the class described, comprising a clip member hooked at its upper and lower ends to overlie a rail base and underlie a tie plate, the upper hook of said member sloping downwardly from the sides 80 toward the centre to provide a centrally disposed key seat, the member being recessed in the said seat portion to releasably hold a key, and a key adapted to be driven between the upper hooked end of said member and 85 the upper surface of a rail base, the said key having intermediate its ends an upward projection adapted to enter the seat recess of the clip to hold the key against longitudinal movement.

11. A device of the class described, comprising a clip member hooked at its upper and lower ends to overlie a rail base and underlie a tie plate, and a key insertable between the upper hooked end of the clip and 95 a rail base and formed to engage at its ends with the rail base and intermediate its ends with the clip, the upper hooked end of the clip and the key having co-operating surfaces so formed that the clip will rockably 100 support the key for movement in planes longitudinal and transverse of the clip to automatically assume a stable position.

12. A device of the class described, comprising a clip member to be disposed longitudinally of a rail and having projections on opposite sides thereof, one to engage the bottom of a tie plate and the other to engage the top of a tie plate, and a key adapted to be driven in compression between said clip 105 member and a rail base to hold the clip to a rail and tie plate.

13. A device of the class described, including a body member having a pair of spaced lateral projections at one side adapted to engage the lower surface of a tie plate, and a lateral projection from the opposite side intermediate the two first named projections adapted to engage the upper surface of a tie plate, and a further lateral projection on the same side as the two first named projections adapted to overlie a rail base.

14. A rail anchor for use with a tie plate and spike, comprising a body, downwardly extending hooked extensions thereof adapted to pass through spike holes of the plate and engage the under surface thereof, said body being adapted to engage the edge of

6
a rail base above the plate, the body and its extensions being formed for engagement at points above and below the edge of the rail base by a spike driven through the tie plate, 5 whereby the body is held in predetermined position and against separation from the tie plate and rail, the said body being adapted for engagement with a key driven between itself and the rail base.

10 15. In combination with a device according to claim 14, a key adapted to be driven between said body and the rail to hold the body against tipping toward the rail, and a projection from said body adapted to engage a tie plate and hold the body against tipping away from the rail.

15 16. A rail anchor, comprising a clip adapted to engage under a tie plate and to overlie a rail base, a key adapted to be driven between said clip and a rail base to hold the clip in position and against tipping toward the rail, and means to be inserted between the clip and an abutment of a plate to hold the clip against tipping away from the rail.

20 25 17. In a rail anchor, a clip member to overlie a rail base having a pair of spaced supporting points for engagement with one surface of a tie plate and a third supporting point for engagement with the opposite surface of the plate and disposed intermediate the first named points.

25 30 35 18. In a rail anchor, the combination with a rail and plate thereunder, of a clip member to overlie the rail base and underlie the plate, and a key engaging said clip member at a point intermediate the key ends and engaging the rail base at points spaced in the direction of rail length on opposite sides of the point of engagement with the clip member.

40 45 50 19. In a device of the class described, the combination with a rail and shouldered tie plate, of an anchor device adapted to hold the rail down to the tie plate and a spike adapted to be wedged between the tie plate and said anchor device to hold the rail in compression between the anchor device and plate shoulder.

the rail to the plate, and means to be located in the plate aperture and to hold it against movement away from a rail.

30. A device of the class described comprising in combination with an apertured plate to underlie a rail a member hooked at its upper and lower ends to overlie the base of a rail on said plate and to pass through the plate aperture and underlie the plate, a key adapted to be inserted between the upper hooked end of said member and the base of a rail on the plate in contact with both, and a spike adapted to be driven through the plate aperture to hold the hook member against movement away from a rail.

31. A device of the class described comprising a clip member hooked at its upper and lower ends to overlie a rail base and underlie a tie plate, a key to be inserted between the upper hooked end of said member and a rail base in contact with both, and separate means to be disposed on the opposite side of said clip from a rail to hold the clip and key against movement away from a rail.

32. A device of the class described comprising a clip member formed to engage under a plate and to project above the base of a rail on said plate, the upper part of said clip member being turned downwardly over the rail base to limit upward movement

thereof, and a single member to position the clip in operative relation with a rail and plate.

33. Means to clamp together a rail and an underlying device including a double hooked member to underlie said device and overlie the rail, and a resilient clamping member adapted to engage the rail and to be tensioned between the rail and hooked member.

34. Means to clamp together a rail and an underlying device including a double hooked member to underlie said device and overlie the rail, and a resilient clamping member adapted to engage the rail and to be tensioned between the rail and hooked member, and means to hold the clamping device against movement laterally away from a rail.

35. Means to clamp together a rail and an underlying device including a double hooked member to underlie said device and overlie a rail base, and a resilient clamping member adapted to be forcibly inserted between a rail and said hook member and to exert wedging action in application and to be tensioned between the rail and hook member.

In witness whereof, we have hereunto set our hands.

FRANCIS W. COOPER.
HENRY STEADWORTHY.
